UNITED STATES PATENT OFFICE.

BERTRAM MORDAUNT CHAMBERS, OF LONDON, ENGLAND.

ARTICLE-HOLDING MEANS.

Application filed November 12, 1923. Serial No. 674,296.

To all whom it may concern:

Be it known that I, BERTRAM MORDAUNT CHAMBERS, of 59 Cadogan Square, London W., England, a subject of the King of Great Britain, have invented a new Article-Holding Means (for which I have filed applications in Great Britain No. 31,000 filed the 13th November, 1922, and No. 20,364 filed the 10th of August, 1923), of which the following is a specification.

This invention relates to an article holding means or device for securing in position bedclothes, or for attaching an object such as a label or plaque to cloth or the like, or for any similar purpose for which a separable button may be used. For example, in one form it is particularly suitable for retaining a quilt eiderdown on a bed which otherwise, and especially if of silk or satin, might readily be displaced by the occupant. In a modification, the device may be combined with an ornamental display portion which might bear, for example, advertising matter, sale prices or descriptive matter. The invention might also be used for securing a card or similar object to cloth or in a simple form may be used as a badge, souvenir button or the like. If the device is to be used as a label, the display surface may be a removable slip of paper or cardboard or of material on which chalk or like marks may be inscribed and afterwards erased.

According to this invention, a small hook-like wire member is provided, which is so formed as to enter cloth or the like upon being slightly pressed thereon and partially rotated. This member comprises preferably a length of stiff wire bent so as to form two arcuate barbs with points, approximately concentric and each with a slight helical inclination so as to present the points downwards. More than one pair of such points may be provided by a suitable arrangement of the pieces of wire. In order to facilitate the retention of the points in the material, they may be made with a partially spiral, as well as slightly helical, bend, or they may be suitably crimped or kinked. The cloth-engaging member is, according to the invention, fitted with a head which may conveniently be simply a disc-like member, easily formed by pressing and which may be of ornamental colour or design or the surface of which may be the display surface above referred to. This

head is attached to the cloth-engaging member, through the medium of a socket attached to the head being engaged by an elongated and upwardly projecting loop formed by the wire. The head thus resembles the larger member of a well-known type of two-piece collar stud. In this case, a small disc of metal with a central aperture may be fitted to the cloth-engaging portion to limit the depth to which the barbs may enter the cloth and partially to secure the device by a jamming or wedging action which will be made clear later. The invention will be better understood with reference to the drawings herewith, in which details of construction and different types are shown.

Fig. 1 is a perspective view of the invention. Fig. 2 is a side elevation partly in section and Figs. 3 and 4 are sectional views showing the method of construction of the head portion of the device.

In Figs. 1, 2, 3 and 4 is shown a head member 1, directly attached to the cloth-engaging hooks. The method of attachment of Fig. 1, is illustrated in Fig. 2. The head 1 is formed in the manner of many small "vanity mirrors" etc., namely, of two pieces, an outer shell 1^a having its edges 1^b pressed over the edge of a metal or similar disc 1^c. The cloth-engaging member in Figs. 1 and 2 comprises a length of wire 2 bent upon the inside face of the back of the head member as is illustrated more particularly in Fig. 2 by dotted lines, and having its ends projecting through the back and formed into radially and downwardly projecting hooklike portions with arcuate and slightly helical pointed ends 2^a. The formation of the length of wire 2, shown in dotted line, lies within the head, the wire passing through an approximately central hole 3 and thus the cloth-engaging portion is more or less permanently a part of the device in this form. The hole 3 may be in the part 1^a or 1^c according to whether the flat or slightly convex side of the head 1 is desired to be the display surface. It will be understood that this form of the invention finds its main application as a label or badge and that a price or other matter is in such a case suitably applied to the display surface of the head 1. Fig. 3 shows a modification in which the length of wire 2 is of simpler form, two holes 3^a being provided through which it passes, and two simple

arcuate barbs 2^b are provided. In Fig. 4, two pieces of wire 2 are employed, forming four barbs 2^c which may be shorter than the barbs 2^b, for example, and yet secure the head 1 just as firmly. It will be realized that the forms described in connection with Figs. 1, 2, 3 and 4 are all intended simply as a label or ticket. The device is applied simply by placing the points against the cloth to which it is desired to secure it, and partially rotating. The head 1 is again provided constructed as previously described but to this head is secured a short and somewhat flattened tubular socket 4 with preferably a slightly constricted open end 4^a. The cloth-engaging member is a length of wire bent to form an elongated loop 5, the wire further being bent to form a slight constriction 5^a of the loop and then to form two material-engaging arcuate and partially helical barbs 5^b. A small metallic disc 6 with a central aperture is applied to the constricted portion 5^a of the loop. Thus, when the device assembled as shown in Fig. 1 is pressed and partially rotated against the material to be engaged, the points 5^b enter the material and a portion of the latter becomes jammed or wedged between the points 5^b and the disc 6. The points 5^b are preferably formed with fairly sharply angular elbows 5^c which assist in preventing the accidental withdrawal of the device from the material to which it is affixed. This form of the invention is intended to be used primarily in securing an eiderdown to the

bedclothes beneath, and this is achieved by the socket 4 being inserted through a hole in the quilting and being pressed into engagement with the portion 5 when, upon partial rotation of the head 1, the device may be 40 made to engage the cloth underneath. The socket 4 may be secured (referring to Figs. 3 and 4) either to the portion 1^a or 1^c according to whether the upper or lower surface of the disc is desired to be visible. It 45 will be recognized that this form of the device may equally be used for securing cards or papers to cloth, or for other purposes the socket 4 simply being pressed through the paper or through a hole formed 50 therein. It will be realized that certain modifications may be made.

I claim:

1. Article holding means consisting of a head member, a hollow flattened tube fixed 55 thereon, and a piece of wire bent into an elongated loop adapted to enter said tube, the external ends of said wire being bent to form a pair of arcuate and slightly helical barbs.

2. A device comprising a head formed of two pieces, viz, an outer shell and a disc connected therewith in combination with a hollow flattened tube fixed on said disc, and a piece of wire bent into an elongated loop 65 adapted to enter said tube, the external ends of said wire being bent to form a pair of arcuate and slightly helical barbs.

BERTRAM MORDAUNT CHAMBERS.
